[57] CLAIM

The ornamental design for rack for holding books, as shown and described.

DESCRIPTION

FIG. 1 is a perspective view of a rack for holding books showing my new design;

FIG. 2 is a side elevational view, the opposite side being a mirror image thereof;

FIG. 3 is an elevational view showing one of the two identical ends;

FIG. 4 is a top plan view; and.

FIG. 5 is a bottom plan view thereof.

The inner face of the vertical support not shown is the same in appearance as the inner face shown in FIG. 1.

FIG. 1.

FIG. 2.

FIG. 3.

FIG. 4.

FIG. 5.
